SHIRT ENVELOPE

Louis Blumenstock, Brooklyn, N. Y.

Application February 2, 1932, Serial No. 590,384

1 Claim. (Cl. 206—7)

My invention relates to improvements in shirt envelopes, and more particularly has reference to a card closure for laundered shirts usually open at the top and sometimes at the bottom, into which the laundered shirt is slid and may be secured, and is in the nature of an improvement on my co-pending applications S. N. 542,343 and 542,344.

Referring to the accompanying drawings, I have illustrated in Fig. 1 in perspective with the lower part broken away, a suitable form of shirt envelope embodying an application of my invention, showing the shirt in position therein. Fig. 2 is a similar view with the shirt omitted. Fig. 3 is a similar view of a modified view of envelope adapted more particularly for a soft shirt, showing the same therein. Fig. 4 is a similar view with the shirt omitted. Fig. 5 is a modified view with a soft shirt therein, and Fig. 6 is a similar view to Fig. 5 with the shirt omitted.

The back of the envelope preferably extends slightly above the top of the shirt as shown, and may be provided with hanger holes such as 7. The front portion is cut away as indicated at 8, and is preferably provided at the lower front portion with a flap 9, having a hole 10 therethrough which may be split at the sides as shown to facilitate pressing the same over the front button of the neck band as shown in Fig. 1, this form of envelope being more particularly adapted for collarless shirts.

The lower cut out portion 11 may also be provided with a restricted opening 12, at the bottom thereof, to receive the second button 13, of the shirt, thus not only additionally securing the shirt within the envelope, but exposing through the opening 11 the pleat 12, or design of the shirt for identification and, of course, said open-

ings may be covered with "Cellophane" or other suitable transparent material, if desired.

In the modifications shown in Figs. 3 and 4, the upper cut out front portion is preferably provided with supporting means 14, adapted to engage beneath the collar 10 of the shirt, and a flap 15 may also be provided to engage beneath the back of the collar, as shown. The lower portion of the top cut-away part may also be provided with a restricted recess 16 into which the top button of the shirt may be secured, if desired, and a cut out portion 11', may be provided with another button seating 12', as shown.

In the modification shown in Figs. 5 and 6, a similar arrangement to that shown in Figs. 3 and 15 4 is provided, except that the cut out portion 11'' is preferably substantially triangular as shown, and reversed, thereby preventing the shirt from slipping out of the envelope until one or the other of the button engaging means has been released 20 and, it will of course be understood, that several cut out portions such as 11 or 11'' may be employed if desired. In fact various modifications may be made in the construction and arrangement of parts without departing from the spirit 25 of the invention as claimed.

I claim:

A shirt slip of the class described comprising front and back spaced apart walls, said front wall cut away at the top to clear the collar of the shirt, the sides of said cutaway portion extending downwardly below the collar of the shirt, and means at the base of the cut-away portion to engage and hold the top button of the shirt, and in combination therewith an opening 35 through the front of the slip below said cutaway portion also adapted to engage a button of the shirt.

LOUIS BLUMENSTOCK.
